CLAIM

The ornamental design for a two-piece cap assembly for modular panel mounting systems design, as shown and described.

DESCRIPTION

FIG. 1 is an exploded environmental perspective view of a two-piece cap assembly for modular panel mounting systems in an exemplary environment;

FIG. 2 is an assembled environmental right elevation view thereof in an exemplary environment;

FIG. 3 is a top environmental perspective assembled view thereof;

FIG. 4 is an exploded environmental perspective view thereof in an exemplary environment;

FIG. 5 is a top environmental perspective assembled view thereof in an exemplary environment;

FIG. 6 is a frontal elevation view thereof;

FIG. 7 is a rear elevation view thereof; and,

FIG. 8 is a right elevation view thereof.

The broken lines showings of the figures is for the purpose of illustrating environment and forms no part of the claimed design.
